UNITED STATES PATENT OFFICE.

WILLIAM S. SUTTON, OF ROCKFORD, ILLINOIS.

RHEOSTAT.

Application filed October 21, 1922. Serial No. 595,974.

This invention pertains generally to radio or wireless transmission, or reception, and has more particular reference to a rheostat adapted to adjustably supply current to the filament of a vacuum tube, and may be employed in the circuit of the receiving or sending station.

While the principles of my invention may be embodied in rheostats of various sizes, adapted for many different purposes, the one herein shown as illustrating the principles of my invention is particularly adapted for enabling the attainment of a very fine adjustment in the filament circuit of the receiving station. In the operation of a vacuum tube, it is very desirable to supply the filament current through a control means that is capable of very fine and gradual adjustment in order to secure maximum efficiency of the tube.

The resistance coils, customarily employed for the purpose indicated, have prior to my invention comprised a series of convolutions connected at intervals to contact points adapted to be individually engaged by an adjustable switch or contact member. The effective resistance of such a coil could therefore be varied only in stepped intervals limited as to fineness by the total resistance of said convolutions cut into or out of the circuit, and consequently only an approximation of accuracy could be secured with coils of this character.

One of the primary objects of my present invention is to provide a rheostat, which will be capable of substantially infinitesimal adjustments to vary the effective resistance by minute gradations, so that extremely fine and very accurate resistance variations can be obtained.

A further object of this invention is to provide a resistor of the proper proportions and a contact shoe adapted to make sliding contact with said resistor, the parts being so arranged with relation to each other that they may be mounted in a conveniently small space, and operated from knobs in the center of the device, one knob furnishing roughly the approximate resistance, while the other knob provides vernier or fine adjustment for securing a very close and accurate supply of current to the filament.

Another object of the invention is the provision of a rheostat which will be simple, but substantial and durable in construction; one

which can be economically manufactured, and which will be efficient, accurate and reliable in operation.

Other objects and advantages of this invention should be readily appreciated by those skilled in the art as the same becomes better understood by reference to the following description when considered in connection with the accompanying drawings.

Referring to the drawings:

Figure 1 is a medial, sectional view through a rheostat embodying my invention;

Fig. 2 is a fragmentary face view, showing the adjusting knobs;

Fig. 3 is a sectional view on the line 3—3 of Fig. 1;

Fig. 4 is a sectional view on the line 4—4 of Fig. 1; and

Fig. 5 is a detailed sectional view through the contact element taken on the line 5—5 of Fig. 3.

Referring now to the drawings more in detail, reference character 6 indicates generally the front panel of the cabinet in which the various apparatuses of a receiving station are mounted. To the rear or inner face of this panel there is secured a housing comprising a plate 7, and a shell 8 secured to the panel by a plurality of screws 9, or other preferred fastening means.

Within this housing is rotatably mounted the resistance coil, which comprises a series of convolutions 11 wound in spaced relation upon a cylinder or drum 12 made of suitable insulating material and connected by a web or spider 13 to a pinion 14 which is rigidly attached to a shaft 15, journaled at one end in a suitable and preferably insulated bushing 16, and projecting at its other end forwardly of the panel 6, where an operating knob 17 is mounted thereon.

One end of the coil 11 is connected to the web 13 of the cylinder, as indicated by reference character 18, and the other end is embedded in or otherwise fixedly anchored to the insulated portion 12 of the cylinder. A binding post 19 projects at the rear of the shell 8 for the attachment of one of the circuit wires thereto, while its inner end is equipped with a spring wiper or contact member 21 continuously contacting the web 13 of the cylinder, the binding post being mounted in an insulating bushing 22, as shown in Fig. 1, upon the periphery of the casing 8. A second binding post 23 is mount-

ed in an insulating bushing 24, and upon the inner end of this post within the shell there is pivotally mounted a leaf spring contact member 25, extending circumferentially a limited distance around the cylinder 12, and being equipped at its free end with a wiper or brush 26 provided with a groove 27 as shown in Fig. 5, which is adapted to straddle the resistance wire 11, making a good conducting contact therewith, and maintaining the brush and member 25 against accidental displacement from the wire. It will be manifest that when the wires of the circuit are connected to their respective binding posts 19 and 23, the current will flow through so much of the coil as is included between the end 18 attached to the web 13 of the cylinder and that point on the coil which is engaged by the brush 26, by which the current is taken from the coil at this point and carried through the member 25 to the binding post 23. It will also be obvious that the length of that portion of the resistance coil included in the circuit may be varied by rotating the cylinder and thereby the coil, thus varying the effective resistance of this coil.

The mechanism by which the rotative adjusting movement of the cylinder is effected will now be described:

Upon the interior of the shell 8 there is fixedly mounted an internal ring gear 28 disposed in radial alignment with the pinion 14 and between this internal gear and the pinion there is interposed a gear 29 meshing with both the internal gear and the pinion, as shown in Fig. 4, and rotatably mounted through the instrumentality of a stub shaft 31 upon an arm 32, the hub 33 of which is rotatable about the shaft 15 and within a bearing opening 34 formed in the plate 7. A circumferentially knurled knob 35, also rotatably carried by the shaft 15, has a dove tailed connection with the hub 33 of the arm 32, as indicated at 36 (Fig. 1). For purposes of determining the relative position of the knob 35 it is preferably equipped with an indicator or pointer 37, adapted to cooperate with the indices (not shown) suitably positioned on the outer face of the panel 6.

In the operation of my invention the rough or primary tuning is effected by manipulation of the knob 35, which rotates the arm 32 about the shaft 15, and by reason of the intermeshing relation of the gear 29 with the rotatable pinion 14 and the stationary internal ring gear 28, this pinion and consequently the cylinder 12 and the coil carried thereby, are rotated at a greater speed than the rotation of the knob 35. When by this adjustment the effective resistance of the coil has been brought to an approximation of that desired, the final adjustment is secured by slowly manipulating the knob or button 17, which, being directly connected

with the cylinder, moves the cylinder slowly, thus enabling a final accurate adjustment to a fine degree of nicety, which results in accurate regulation of the circuit.

It should be apparent, therefore, that with my improved rheostat, extremely fine gradations of adjustment can be secured, which will result in absolute accuracy of control, such as is incapable of attainment by instruments which necessitate a step-by-step adjustment and are wholly incapable of any variation of resistance between the successive steps.

It is believed that my invention and many of its attendant advantages will be understood from the foregoing without further description, and while I have shown and described a preferred embodiment of the invention, obviously it is capable of a wide variation in its construction, without departing from the essence of the invention as defined in the following claims.

I claim:

1. In an instrument of the character described the combination of a casing, a shaft mounted therein having an element thereon to be rotated therewith in fine and coarse gradations of adjustment, an adjusting knob fixed to said shaft to communicate direct adjustment to said element, an arm rotatably mounted on the shaft, an operating knob connected to said arm, a gear carried by the arm, a pinion fixed with respect to said adjustable element and meshing with said gear, and an internal gear mounted in said casing and meshing with said first mentioned gear, said last mentioned knob being arranged to communicate adjustment to said element indirectly through the transmission recited.

2. In a rheostat the combination of a rotatably mounted resistance coil, a contact member adapted to engage therewith, a primary means for rotatably adjusting said coil relatively to said contact member, comprising a manually operable knob and a planetary step-up transmission between said knob and said coil, said planetary transmission having the planet element thereof moved through its orbit by said knob, and a final means for rotatably adjusting said coil, comprising a knob directly connected with said coil.

3. In a rheostat the combination of a housing, a resistance coil rotatably mounted therein, a contact member mounted on said housing and adapted to contact said coil and to follow the convolutions thereof upon rotation of the coil, means for rotatably adjusting said coil, comprising a pinion fixed with respect to the coil, an internal gear, a gear interposed between said internal gear and said pinion, and a manually operable means for revolving said gear about the axis of said coil, and a second manually operable device directly connected to said coil.

4. In a rheostat the combination of a casing, a shaft mounted therein, a resistance coil carried by said shaft, a movably mounted contact member adapted to engage with and follow the convolutions of said coil upon rotation of the coil, an adjusting knob fixed to said shaft, an arm rotatably mounted on

the shaft, an operating knob connected to said arm, a gear carried by the arm, a pinion fixed with respect to said coil and meshing with said gear, and an internal gear mounted in said housing and meshing with said first mentioned gear. 10
